UNITED STATES PATENT OFFICE.

GUSTAVE TILGER, OF CHICAGO, ILLINOIS.

VEHICLE SIGNAL.

Application filed April 22, 1924. Serial No. 708,132.

To all whom it may concern:

Be it known that I, GUSTAVE TILGER, a citizen of France, and a resident of Chicago, in the county of Cook, State of Illinois, have 5 invented a new and useful Vehicle Signal, of which the following is a specification.

The present invention relates to vehicle signals and particularly to those usually designated as "stop lights."

10. The objects of the invention include the provision of a unique signal device, per se; means for rendering such signal visible at night and for drawing attention thereto when actuated; a novel construction and assembly of parts; and a bracket or fastening means rendering the device readily adjustable to any angle of attachment.

These and such other objects as may hereinafter appear are attained by the novel 20 combination, construction and arrangement of parts, all of which are fully illustrated in the accompanying drawing forming a part of this specification, and in which:—

Figure 1 is a side view of my device, partly 25 in section;

Figure 2 is a back view;

Figure 3 is a horizontal section on the line 3—3 of Figures 1 and 2, and

30 Figure 4 is a side view detail, partly in outline, of the bracket employed for holding the device.

Like reference characters are used to designate similar parts in the drawing and in the specification which follows.

35 The device comprises a barrel or frame 10, ordinarily cylindrical in configuration, preferably highly polished within, and having two or more ports 11 and 12 disposed at angles of about 90 degrees from one another.

40 Insertable from beneath and into barrel 10 is a cap 13 upon which is mounted a light socket 14 carrying a light bulb 15. Current is conveyed to socket 14 and light 15 by conduits 16, preferably supplied with quickly 45 detachable connections with said socket. In the drawing, cap 13 is arranged for attachment to barrel 10 by screw threads, but any other type of connection may be employed.

50 Barrel 10 is closed at its top 17 and said top is perforated to receive the end of a spring later to be described. Affixed to said top 17 is a centrally located and upwardly directed threaded member 18 about which a coil spring 19 is wrapped, the lower section 55 of which is inserted into the hole in top 17 just described.

Arranged about barrel 10 is a second barrel 20 provided with a plurality of ports 21 and 22 disposed at 180 degrees to one another and having a hand 23 of sheet material secured thereto at the wrist 24, the material at said wrist 24 being of two thicknesses highly polished or glazed upon the interior and separated to form a cypher in cross section as is shown in Figures 1, 2, and 60 3. The hand 23 is preferably painted white and highly polished or glazed and the palm of dish configuration. A cap or cover member 25 having a perforation to receive the upper end of spring 19 is firmly secured to 70 barrel 20 such cap being additionally perforated to allow the threaded member 18 to pass therethrough. Pins 26 and 27 are disposed upon the top of said cap 25 for engagement with a bracket 28 to arrest rotative movement of barrel beyond certain predetermined limits, said bracket being adapted to engage about threaded member 18 and to be secured to the inner barrel 10 by a nut 75 29 screwed on member 18 to complete the 80 assembly of the device proper.

Bracket 28 includes an extension portion 28^a forming a guide for a cable housing 30 through which a cable 31 is run from the 85 brake or clutch pedal or other manually operable lever to and partly around the periphery of cap 25 whereby cap 25 may be rotated a distance of about 90 degrees against the tension of spring 19, such rotative movement being limited by pins 26 and 27 as 90 hereinabove indicated.

Additionally bracket 28 has an extension portion 28^b having an arcuate slot 32 in which a bolt 33 is adapted to slide, such bolt after traversing extension 28^b passing 95 through the ends of a loop clamping member 34 pivotally secured to bracket 29 by a rivet or the like 35.

The various parts have been so fully described that a further discussion of their 100 construction and of their assembly would be superfluous. The assembled device is attached to the frame or fender or some other rear portion of a machine with the hand 23 pointing forward and the cable 31 run forward through housing 30 to the brake pedal or other movable lever. Pressure upon the brake pedal exerts a pull upon cable 31 which cable in return rotates barrel 20 a quarter turn, bringing the hand into a transverse position plainly visible from any point 105 in the rear of the machine. Release of the 110

brake pedal allows the hand 23 to assume its normal forward position.

To render the signal readily visible at night, the various ports are employed. In these, panes of glass or composition may be inserted and secured. When the hand 23 is pointing forwardly, ports 11 and 21 register, giving a light of such color as the glass or other material (for example green) inserted into one of said parts may determine. When the hand 23 is rotated a quarter of a turn, parts 11 and 21 cease to register and parts 12 and 22 come into alignment and the color of the glass or other material inserted into either of said parts, (for example red) is flooded onto and upon the palm of hand 23 through wrist 24. Upon release of the cable 31, the green light again becomes visible. It is quite manifest that the light bulb 15 is subjected to a continuous current, and does not of itself move, and that, at night, a constant signal is maintained. The attention of a driver to the rear of the vehicle is instantly arrested by a moving signal in the day time and at night by the change from a small light of one color to a flood of light directed upon a relatively large object. In operation the device is of course positive, and is so simple in its con-

struction that it cannot be readily put out of order.

To replace a light it is only necessary to unscrew cap 13, replace the bulb 15, and replace cap 13.

I claim:

1. In a vehicle signal, a stationary barrel, having a plurality of light ports, a rotatable barrel provided with a light port, a signal upon said rotatable barrel, and a light within said stationary barrel and adapted to play upon said signal when said rotatable barrel is moved, said signal comprising a hand having an enclosed wrist for concentrating the rays of light upon the palm of said hand.

2. A tail light comprising a perforated barrel, a detachable cap for said barrel and having a light socket disposed therein, a hand of opaque material comprising a cylindrical section at the wrist of said hand, a second perforated barrel secured to said wrist, a spring intermediate said barrels, and a cable for actuating said second barrel, angular displacement of said barrel obscuring said tail light and providing warning signals.

GUSTAVE TILGER.
